UNITED STATES PATENT OFFICE.

WILLIAM JAMES HUSSEY, OF STURGEON FALLS, ONTARIO, CANADA, ASSIGNOR TO
HERBERT GUETTLER, OF CHICAGO, ILLINOIS.

BARKING APPARATUS.

1,312,633.

Specification of Letters Patent. Patented Aug. 12, 1919.

Application filed December 27, 1916. Serial No. 139,211.

To all whom it may concern:

Be it known that I, WILLIAM JAMES HUSSEY, a British subject, residing at Sturgeon Falls, Province of Ontario, Dominion of Canada, have invented certain new and useful Improvements in Barking Apparatus; and I do hereby declare the following to be a full, clear, and exact description of the invention, such as will enable others skilled in the art to which it appertains to make and use the same.

The present invention relates to bark-removing apparatus of the type in which blocks of wood from which the bark is to be removed are tumbled in a rotating drum.

It is an object of the present invention to provide an improved means for supporting the drum for rotation.

While the invention is in some respects of general application, the preferred embodiment hereinafter disclosed comprises a drum open at both ends and adapted to receive blocks of wood at one end and to deliver them, after barking, through the other end, the separated bark being liberated through openings in the side of the drum and the blocks of wood under treatment being periodically immersed in water as they cascade and tumble in the drum, or being barked dry, if desired.

It is a further object of the invention to provide driving means suitably coöoperating with the drum-supporting means to cause reliable and efficient operation and proper distribution of the weight of the moving elements and their load of wood.

The details of the preferred embodiment and various objects and advantages inherent in its construction will be made clear by the following detailed description, which is to be taken in conjunction with the accompanying drawings, wherein—

Figure 1 is a side elevation of the barking apparatus;

Fig. 2 is an end elevation of the same showing the discharge end;

Fig. 3 is a section on the line 3—3 of Fig. 1;

Fig. 4 is an elevation of one of the drum supports;

Fig. 5 is a detail showing one of the drum guides; and

Fig. 6 is a section through the annular sprocket whereby the drum is rotated.

In the drawings, the drum 1, wherein the blocks of wood are tumbled, is of cylindrical shape and comprises a plurality of flanged rings 2 to which are secured angle bars 3 having inwardly projecting flanges which give to the inside of the drum an irregularity of surface sufficient to cause progressive cascading of the pile of wood therein when the drum rotates. These bars 3 are spaced far enough apart to form long, narrow slots in the wall of the drum through which the bark detached from the blocks may escape.

The drum is arranged for rotation in a tank 4 having an outlet conduit 5 covered by a grating 6 and controlled by a valve 7, so that, when desired, the tank may be filled with water and the blocks of woods thus be periodically immersed in the water as the drum rotates. Preferably, the drum carries flights or combs 8 secured to its periphery and arranged to sweep the curved concentric bottom of tank 4 and lift therefrom over the edge 9 of the tank such detached bark as has passed through the slots of the drum into the tank. The bark so delivered over the edge 9 of the tank can then be carried away by a suitable traveling conveyer 10.

The means for supporting and driving the drum (and it is to this that my present invention is particularly directed), comprises a framework having uprights 11, top members 12, and cross-beams 13, and some at least of the cross-beams 13 are provided with drum supports 14 which may be in the form of downwardly extending rigid brackets, as shown, bolted to the cross-beams 13 and provided with rollers 15 to engage a ring 16 encircling the drum, the engagement taking place at a point above the median line of the drum. Preferably, but not necessarily, each member 14 is in two parts with a tongue and groove connection at 17 and a clamping bolt 18. The roller 15, with which each part is provided, is preferably flanged, and ring 16 is preferably of I-beam construction, so that the flanged rollers 15 can bear against the outermost flange and so hold the drum in suspended relation to tank 4 but free to rotate in the tank when desired.

The drum supports above described may be arranged in pairs, as shown (Fig. 3), and four such pairs with their coöoperating rings 16 will serve to support a barking drum of usual dimensions.

As a means for rotating the drum in its supports, there may be provided a sprocket or annular rack 19 encircling the drum near its center and secured thereto as by being 5 clamped between adjacent flanged rings 2. Passing over this sprocket 19 is a driving chain 20 actuated by a sprocket on a drive shaft 21 which can be driven by an attached sprocket 22 and coöperating chain 23. Preferably 10 shaft 21 is positioned approximately above the upwardly moving side of the drum, for the upward pull of the chain thereby compensates to some extent for the unequal distribution of the load of wood in the drum and so tends to equalize the downward pull on the two supporting brackets 14 of each pair. As a means for steadyng the drum during rotation, guide wheels 24 may be mounted on either side near the ends of 15 the drum to engage a guide ring 25, (Fig. 5).

When the drum is in action, the blocks of wood to be barked are delivered to the open intake end thereof by a conveyer 26 and are delivered down a chute 27 and thereafter, 20 because of the rotation of the drum, are caused to cascade in the drum, sliding over one another and thereby gradually detaching the bark which is allowed to escape through the longitudinal slots into the water tank and from there is removed over the 25 edge 9 of the tank by the paddles or combs which periodically sweep through the water and scrape off the bottom of the tank. An end wall of planks secured to uprights 11 30 prevents the wood blocks from escaping at the open intake end of the drum. By the time the blocks of wood reach the discharge end of the drum the bark will have been removed from them and they may be permitted 35 to escape over the plank barrier 28 (Fig. 2) by which this otherwise open end of the drum is in part closed. The blocks thus liberated fall on an inclined grating 29 where they may be washed off by a water spray 40 from pipe 30 (Fig. 1) and then delivered to a conveyer 31 (Fig. 2) for transportation elsewhere.

When the blocks of wood are to be barked dry, as, for instance, when they are of hemlock, valve 7 is opened to draw the water 45 from tank 4, and, except that the blocks are not periodically immersed in water during tumbling, the mode of operation is essentially that above described.

With a drum thus supported on rollers 50 which are suspended from above and engaging the rings at a point above the median line of the drum, there are no obstructions in the water tank about or behind which bark can accumulate, and by making the tank relatively shallow, as shown, and substantially concentric throughout with the drum and free from any bark-receiving corners or pockets, the combs or flights 55 operate with effectiveness and without substan-

tial consumption of power in sweeping the bark from the tank and over the edge thereof for delivery to conveyer 10.

The drum supporting means is rugged in construction and simple in design, is easy 70 to lubricate and not easily deranged, it holds the drum from swinging or jumping out of position, and at the same time will continue to give reliable support and guidance even though the drum may be distorted in shape 75 either from accident of manufacture or because of twisting or weaving under the enormous strains to which it is subjected in commercial use. These drums may have a length of thirty feet, or more, and a diameter of 80 eight to ten feet, or even more, and when such a drum is carrying its normal charge of wood, the weight aggregates many tons.

I claim:

1. In a bark removing machine, the combination of a rotatable drum, supporting rollers on which said drum may turn, said rollers engaging the drum above its median line and suspending it from above while leaving the space beneath the drum unobstructed, and means for rotating said drum on said rollers. 85

2. In a bark removing machine, the combination of a drum wherein blocks of wood may be tumbled for removal of their bark, a 90 framework above said drum, rigid means suspended from said framework and rotatably supporting said drum above its median line, and means for rotating said drum while thus supported. 95

3. In a bark removing machine, the combination of a rotatable drum in which blocks of wood may be tumbled for the separation of their bark, said drum having openings in its side through which the separated bark 100 may escape from the drum, a framework, a plurality of brackets secured to said framework and supporting said drum above its median line, said brackets having rollers to facilitate rotation of the drum, and means 110 for turning said drum on said rollers. 105

4. In a bark removing machine, the combination of a rotatable drum adapted to continuously receive blocks of wood at one end and to discharge them at the other end, said 115 drum having bark discharging slots, a tank adapted to contain water wherein the drum may rotate, rings encircling said drum, rollers engaging said rings above the median line of the drum, and rigid means supporting said rollers from above and leaving an unobstructed space beneath the rotating drum. 120

5. In a bark removing machine, the combination of a rotatable drum adapted to continuously receive blocks of wood at one end and to discharge them at the other end, said 125 drum having bark discharging slots, a tank adapted to contain water wherein the drum may rotate, said tank having a concave bot-

tom which throughout is substantially concentric with the drum, rigid supporting brackets, provided with rollers engaging the drum at a point above its median line to suspend the same from above at such point, and means carried by the drum for continuously removing the bark from the tank as the drum rotates.

6. In a bark removing machine, the combination of a rotatable drum adapted to continuously receive blocks of wood at one end and to discharge them at the other end, said drum having bark discharging slots in its side, a tank adapted to contain water where-
10 in the drum may rotate partly submerged to periodically submerge the wood under treatment, said tank having a concave bottom which throughout is substantially concentric with the drum, said tank being unob-
15 structed from end to end, a supporting framework, rigid brackets suspended from said framework, rollers carried by said brackets, rings encircling said drum and engaging said rollers to suspend the drum

therefrom, means for continuously rotating 25 said drum on said rollers, and means carried by the drum for continuously lifting the separated bark over the edge of the tank as the drum rotates.

7. In a bark removing machine, the combination of a drum adapted to continuously receive blocks of wood at one end and to discharge them at the other end, said drum having bark-discharging slots in its side, an annulus encircling said drum and having an 30 engageable inner periphery and means rotatably supporting said drum from said inner periphery, substantially as described.

8. In a bark removing machine, the combination of a drum, a tank, an annulus en- 40 circling said drum and having an engageable inner periphery and means outside of the tank and engaging and supporting the drum from such inner periphery above the level of said tank while permitting the drum 45 to rotate on such supporting means.

In testimony whereof I affix my signature.
WILLIAM JAMES HUSSEY.
